Thomas Barry, of New York, N. Y.
Letters Patent No. 927 Dated Aug. 25, 1857.

The schedule referred to in these Letters Patent, and making part of the same.

Be it known, that I, Thomas Barry, of the City and State of New York, have produced a new and original design for the plates of a Stove, known as the Home Stove; And I declare that the annexed delineations forming part of this specification, are accurate representations of the said plates, which are combined to form said stove, with their ornamental parts; the side plates not represented, being symmetrically similar to those represented.

What I claim and desire to secure by Letters Patent, as my production, is the combination of and arrangement of ornamental figures and forms, represented in the accompanying drawings, forming together the ornamental design for the plates of a Stove.
